SAND CONDITIONING MACHINE

Stanley B. Davies, Kingston, Pa., assignor to
 Royer Foundry & Machine Company, Kings-
 ton, Pa., a corporation of Pennsylvania

Application July 8, 1938, Serial No. 218,210

2 Claims. (Cl. 22—89)

The present invention relates to a sand conditioning and treating machine.

An object of the invention is the provision of a machine of this character capable of receiving 5 poured molds, shaking out the casting from the sand, screening and tempering the sand and transferring the tempered sand to a sand treating and throwing mechanism from which the treated sand is discharged ready for use in subsequent molding operations.

A further object is to provide a portable mechanism which will permit the molds to be placed on the forwardly moving machine and the conditioned sand discharged forwardly of the movement of the machine at a specified point convenient for reuse.

Another object is the provision of a sand treating mechanism which is capable of movement relative to the rest of the machine whereby the treated sand may be discharged in different directions forwardly of the machine; that is, the treated sand may be discharged either to the right or left or directly in front of the machine, as desired.

A further object is to provide means carried by and normally located in front of the vehicle, to convey the molds to the shakeout mechanism, said means being movable to inoperative position above the shakeout when the vehicle is to be transported to various places.

A still further object is the provision of means associated with the sand treating mechanism, for controlling the discharge of the treated sand from said mechanism.

Another object is the provision of a self-propelled supporting vehicle of the endless track or crawler type having means for effectively steering and operating the vehicle.

With the foregoing and other objects in view, 40 the invention will now be more fully described, reference being had to the accompanying drawings, in which:

Figure 1 is an elevation of one side of the machine, with the mold feed conveyor in operative position.

Figure 2 is an elevation of the other side of the machine as shown in Figure 1.

Figure 3 is a vertical transverse section through the shakeout, and bucket elevator.

Figure 4 is a transverse section through the mold feed conveyor.

Figure 5 is a detail view in plan showing the means for directing the screened material to the elevator, and

Figure 6 is a detail of the propelling and steering mechanism for the machine.

The present invention is particularly adapted for use in foundries. It has been the custom in the past to provide separate machines for shaking out the molds and for treating the separated sand for reuse. Furthermore, before the separated sand is acted upon by the conditioning and treating mechanism, it is customary to subject it to a tempering operation. Consequently, 10 in order to properly prepare the sand for reuse, it has been necessary to perform a number of separate operations, often in different parts of the foundry, requiring the services of numerous operators.

The present invention is designed to eliminate these objectionable features and to provide a compact unit capable of receiving the molds after they have been poured and to discharge the conditioned sand ready for reuse. At the same time, 20 the castings are collected and conveniently retained at the rear of the machine where they are accessible for immediate removal, as desired.

Referring now to the drawings, and particularly to Figures 1 and 2, the numeral 10 designates generally the machine forming the subject matter of the present invention. This machine is self-propelled and is preferably mounted on a vehicle of the endless track type having the usual pair of crawlers or tracks 11, each of which is provided with front and rear sprocket wheels 12 and 13 respectively. The means for operating the crawlers and sprockets will be described in detail hereinafter.

The machine is provided with a sub-frame 35 mounted on the endless track mechanism, and this comprises a pair of outside longitudinally extending beams 14 which are directly supported by the sprocket shafts 15 and 16 respectively, connecting the front and rear set of sprocket 40 wheels 12 and 13. A plurality of cross beams 17 are mounted on the beams 14, and these connect with interior longitudinally extending beams 18 also forming part of the sub-frame. Furthermore, the sub-frame includes a set of longitudinally extending beams 19 which are mounted on top of the cross beams 17. It is to be understood that this construction of crossed beams may be varied if desired, although the present arrangement has been found to be very effective 50 in supporting the various elements of the machine.

Referring particularly to Figures 1 and 3, there is disclosed a shakeout and screening mechanism 20 which extends substantially longitudinally of 55

the machine and is directly supported on the longitudinally extending beams 19 of the sub-frame. This shakeout is of the general type shown and described in Patents 1,860,480 and 5,202,800 to Royer, and therefore will not be described in detail other than to state that it comprises a pair of grids or grills 21 and 22 which are disposed in substantial parallelism and given oppositely timed, translational movement on a 10 substantially circular orbit by means of cams 23. It is to be understood, however, that the shakeout 20 is particularly designed for the present machine and that it is adapted to receive the molds at the front of the machine and to separate the sand from the castings and follow-up 15 boards. The castings and boards will gradually move on the grids 21 and 22 to the rear of the shakeout and eventually pass under the weighted arms or sweeps 24 and fall into a tote box 25, 20 which is removably mounted on the beams 18 and may be replaced by a like box when it has been filled with castings.

Referring particularly to Figure 3, it will be observed that the shakeout 20 is provided with 25 a discharge hopper 26 mounted below the grids 21 and 22 with its lower end terminating directly above the upper run of a belt conveyor 27. This conveyor is suitably supported transversely of the sub-frame and is adapted to receive the separated sand from the hopper and deposit it into the lower end of a bucket elevator 28. The upper run of the belt conveyor 27 is surrounded on three sides by a hopper-like confining frame 29 which is adapted to guide and 30 retain the sand as it is transferred from the hopper 26 to the bucket elevator 28. The open side of this frame faces the bucket elevator and at this point, there is provided a diagonal deflector plate 29' extending above and substantially transversely of the belt 27. One end of 35 this plate terminates short of the side of the frame 29 which is adjacent the up side of the bucket elevator 28, and thereby deflects or diverts the material thereto. This arrangement is 40 essential, since otherwise, the belt 27 would carry a substantial portion of the material to the down side of the elevator, causing the material to jam up in the elevator and impair the efficiency of the machine.

50 At a point between the shakeout and the bucket elevator are positioned a pair of spray pipes 30 which are adapted to spray water or any other suitable liquid down upon the sand to give it a preliminary tempering before it 55 passes into the bucket elevator. The water or other liquid may be supplied to the pipes 30 from a tank or any other suitable supply means (not shown).

The bucket elevator 28 is enclosed in a casing 60 30 whose base is supported by the beams 17 and 18 of the sub-frame. Furthermore, this casing is also positioned between the longitudinally extending beams 31 of an auxiliary frame structure which is supported on the sub-frame 65 by means of the upright beams 32 (see Figs. 2 and 6). The bucket elevator may be of any desired formation and is provided with a plurality of buckets 33 mounted on an endless chain 70 or belt 34. The upper supporting sprocket of the chain 34 is mounted on a shaft 35 journaled in the upper portion of the casing 30'. The shaft extends through the casing and carries a pulley 36 which is connected to an operating motor 37 by means of a belt 38. The motor 37 is sup-

ported on a shelf 39 carried by one wall of the casing 30' (see Figs. 1 and 2).

The sand, after being preliminarily tempered by the water issuing from the spray pipes 30, enters the lower end of the casing 30' and is elevated by the buckets 33 to the top of the casing where it is discharged through the discharge spout 40 into the hopper 41 of a sand conditioning and treating mechanism 42. This mechanism is of the type described in Royer Patent No. 1,559,915, and will therefore not be described in detail herein except to state that it comprises a rapidly rotated sand treating belt 43 which receives, conditions and then throws the treated sand at a considerable distance in advance of 10 the machine. The belt 43 is operated by a motor 44 which, in addition to the mechanism 42 is supported upon a frame or base 45. This base is carried at the front of the auxiliary frame composed of the beams 31 and 32 and is pivotally 15 mounted thereon adjacent the rear of the base 45 to permit the sand conditioning mechanism 42 to swivel on the machine (see Fig. 2). The front of the base 45 is supported upon rollers 46 carried by the auxiliary frame which facilitates the pivotal movement of the mechanism 42. At the rear of the base an arm 47 is connected to and projects laterally from the standard 48 constituting the pivot point about which the sand conditioning mechanism is adapted to 20 swivel. The outer end of the arm 47 carries a nut 49 having a threaded opening which receives the threaded end of an operating shaft 50. This shaft is mounted on one of the longitudinally extending beams 31 of the auxiliary 25 frame and terminates in an operating wheel 51 adjacent the operator's seat 52. By rotating the shaft 50, the nut 49 is moved forwardly and rearwardly on the shaft and, in turn, moves the arm 47. This has the effect of rotating the 30 base 45 and with it the mechanism 42 about the pivot 48 whereby the conditioning belt may be moved to either side of the machine for discharging the conditioned sand at various points in advance of the machine. The rollers 46, of 35 course, facilitate the movement of the base and mechanism 42 about the pivot 48.

In addition to pivotally mounting the sand conditioning mechanism to permit the conditioned sand to discharge at various points in 40 advance of the machine, means are also provided to control the throw of the sand from the conditioning belt 43. This means comprises a sand deflector 53 (see Figs. 1 and 2) pivotally 45 mounted on the mechanism 42 above the top run of the belt 43 and a guide chute 54 spaced from the deflector 53 and pivotally mounted on the mechanism below the upper run of the belt 43. The deflector is adapted to deflect the stream of conditioned sand as it is discharged from the 50 belt 43 and is capable of being raised and lowered to different positions of adjustment with respect to the belt 43. The means for effecting this 55 adjustment comprises a connecting rod 55 pivoted to the deflector and having its lower end connected to a rock arm 56 rigidly connected to a worm wheel 57. This wheel, in turn, meshes with a worm 58 fixed to an operating shaft 59 so as to rotate therewith. This shaft, similar to shaft 50, extends rearwardly to a point convenient to the operator's seat 52 and has a hand wheel 60 secured to its rear end. By rotating this hand wheel, the shaft 59 will likewise be rotated and transmit movement through the worm wheel to the connecting rod 55. This will 65

raise and lower the deflector, as desired. With respect to the chute 54, this is capable of adjustment through the supporting rod 61. As will be observed, the lower end of this rod is provided with a plurality of notches 62 engageable with a horizontal bar 63 carried at the front of the base 45 of the sand treating mechanism. With this construction, the conditioned sand may not only be discharged to one side 10 or the other of the machine, as desired, but by adjusting the deflector 53 and the chute 54, the stream of sand as it is thrown from the belt, may be controlled to permit it to be discharged at any convenient location.

15 Referring again to Figures 1, 2 and 4, there is disclosed means for conveying the molds upwardly and discharging them into the front of the shakeout 20. This means comprises a longitudinally extending frame member 64 in which 20 is supported a belt feed conveyor 65 having spaced flights 66. In operative position the frame and belt are inclined forwardly and downwardly to a position convenient to permit an operator to easily place a poured mold at the 25 front of the belt where it will be conveyed upwardly and discharged onto the front of the shakeout mechanism 20. The belt is operated by a motor 67 carried at the rear of the frame 64. The forward end of this frame is supported 30 on a pair of rubber tired wheels 68, and in operative position the frames 64 and belt 65 are moved forwardly in advance of the rest of the machine. When, however, it is desired to transport the machine to a different part of the 35 foundry or to another location, means are provided to raise the belt 65 to an inoperative position on the machine over the shakeout 20.

This means comprises an auxiliary frame consisting of forward and rear uprights 69 and 70 respectively, of varying height. These uprights support a pair of rails 71 which are inclined forwardly. The rails are of substantially U-shape formation in cross-section and are adapted to receive rollers 72 carried by and projecting outwardly from each side of the frame 64. The extreme front end of each rail is fashioned so as to provide a wide entrance portion 73 for receiving the rollers 72 and for guiding them into the narrow portions of the rails. These entrance 45 portions 73 also constitute adequate supports for the rubber tires 68 when the frame 64 and conveyor 65 are raised to inoperative position.

The means for moving the frame and conveyor to inoperative position comprises a cable 74 having one end connected to the motor support 75 while its other end is wound about a pulley 76 mounted on the shaft 77 of a motor 78. This motor 78 is mounted at the extreme upper end 50 of the rails 71 and may be of any desired type. It is preferred, however, that some sort of braking means (not shown) be associated with the motor for maintaining the conveyor frame 64 in inoperative position. In this connection, however, a positive locking mechanism is also 55 included as a part of the mechanism. This comprises a hook element 79 projecting rearwardly from the frame 75 and engageable with a safety latch 80 pivotally mounted on a bracket 81 carried at the upper end of the rails in front of the motor 78. An operating handle 82 is connected 60 to the latch 80 for swinging it into and out of engagement with the hook 79. In order to positively maintain the conveyor 65 in its operative down position, a pin 83 is provided and this is adapted to be slipped into suitable openings in

one of the rails 71 so as to engage a portion of the motor frame 75. This will positively prevent the conveyor from backing up on the rails when the conveyor is in operative position and when it moves forwardly with the machine. 5

With this construction it will be apparent that the conveyor 65 may be maintained in its upper inoperative position as long as desired. When, however, the machine is to be operated, it is merely necessary to actuate the handle 82 and 10 release the latch 80 from the hook 79. At the same time, the motor brake or other suitable mechanism associated with the motor 78 may be released to unwind the cable 74 and permit the conveyor to move down the rails 71 to its operative position, as shown in Figures 1 and 2. In 15 this position it will be observed that the rear most set of rollers 72 remain on the rails 71 whereby the upper end of the frame 64 is adequately supported in operative position. Thereafter, the pin 83 is slipped into position to lock 20 the conveyor against upward movement on the rails. The machine may then be moved forwardly into any desired position where operators may place the poured molds onto the front 25 of the feed conveyor 65. This may be accomplished when the machine is either stationary or moving forwardly. The molds will be transported up the feed conveyor 65 and dropped upon the shakeout 20, where the grids 21 and 22 30 will shake out the sand from the castings and follow-up boards or other parts of the molds which are placed on the conveyor. The castings, follow-up boards, and other extraneous matter will be moved rearwardly and eventually drop into 35 the tote box 25. The sand will be screened through the grids and will drop upon the transversely mounted belt conveyor 27 where it will be transported to the lower end of the bucket elevator 28. During this movement, the sand will 40 be given a preliminary tempering as it passes under the spray pipes 30. The said will then be raised to the top of the bucket elevator and discharged into the sand conditioning mechanism 45 42 where the rapidly rotating belt 43 will condition and treat the sand and discharge it forwardly at a distance in advance of the moving machine.

By reason of the swivel mounting of the sand conditioning apparatus the sand may be delivered 50 either directly in front of the machine or to one or the other sides thereof. Furthermore, the distance to which the sand is discharged forwardly by the belt 43 is controlled by the deflector 53 and the chute 54. Thus, in the present device the poured molds may be placed upon the front of the machine and the conditioned sand discharged at this end and deposited at a point convenient for reuse. At the same time, the castings will be collected and may be removed, as desired. 55

It is to be understood that while the drawings show the preferred arrangement of the conditioning apparatus, this member may be located so that it can pivot about the rear portion 65 of the machine for discharging the conditioned material at that point. To accomplish this, it would be necessary to reverse the mounting of the bucket elevator on the sub-frame. 60

Any suitable source of power, such as the motor 84, may be utilized to operate the grills 21 70 and 22 of the shakeout 20, while another motor 85 is provided for operating the transversely arranged belt 27. It is, of course, understood that any other suitable means may be utilized for 75

operating the several units of the present machine. However, the use of electric motors is preferred since they may be conveniently controlled by the operator from the switch board 5' located adjacent the seat 52 (see Fig. 2).

Referring now to Figures 2 and 6, there is disclosed the mechanism for propelling the vehicle and operating the endless track mechanism. The source of power for this mechanism comprises 10 a motor 86, although any other suitable power means may be employed. Power is transmitted to a clutch 87 through any suitable reduction gearing 88. This clutch is connected directly to the transmission 89 which is connected through 15 a universal joint 90, to a differential 91. This differential is not shown in detail, since it may be of any desired construction provided with driven shafts 92 and 93. Each shaft carries a sprocket gear 94 which transmits power through 20 sprocket chain 95 to the sprocket gear 96 mounted on a cross shaft 97. This shaft 97 carries the rear sprockets 12 of the crawler mechanism 11.

Brake drums 98 and 99 are secured to the outer ends of the shafts 92 and 93 respectively, and 25 these are associated with external brake bands 100 and 101 respectively. Brake band 100 is operatively connected through linkage mechanism 102 to arm 103 rigidly connected to one end of a cross rod 104 mounted in the frame of the machine. Likewise, linkage mechanism 105 operatively connects the brake band 101 with an arm 106 mounted on the other end of the cross rod 104. It will be observed that the arms 103 and 106 are mounted at different angular positions 30 about the rod 104. This structure is provided to effect steering of the vehicle; that is, the arrangement is such that when the rod operating lever 107 is in neutral position, no braking pressure will be applied to either of the brake drums 98 or 99. However, when the lever is moved 35 either forwardly or rearwardly, braking pressure will be applied to one or the other of the drums and thereby retard or stop the rotation of one or the other of the stub shafts 92 and 93. If braking pressure is applied to drum 98, this will have 40 the effect of retarding the rotation of shaft 92 and accelerate the rotation of shaft 93 through the differential 91 and thereby effect a movement of the vehicle to the left. Conversely, when braking pressure is applied to the drum 99, rotation of shaft 93 will be retarded, and in a like manner the vehicle will be moved to the right. Lever 108 controls operation of the clutch 87, while lever 109 effects operation of the transmission 89.

55 All of the operating levers for the vehicle and for the sand conditioning and treating mechanism are placed conveniently to the seat 52 whereby a single operator may easily and effi-

ciently steer the vehicle to the desired point where other operators will be available to place the poured molds upon the feed conveyor 64 leading to the shakeout. Thus, with the present machine, it will be apparent that numerous operations which it has heretofore been necessary to perform with separate machines, are efficiently carried out by a single machine and by a minimum of operators.

It will be understood that the invention is not 10 limited to the details of construction shown in the drawings and that the examples of the use of the device which have been given do not include all of the uses of which it is capable, and that the phraseology employed in the specification is for the purposes of description and not 15 of limitation.

I claim:

1. In a device of the character described, a frame, a screening mechanism supported longitudinally of the frame and adapted to receive molds, shakeout and separate castings from sand, an elevator mounted on the frame at one side of the screening mechanism, a conveyor supported transversely of the frame and screening mechanism and positioned below the latter to receive the screened sand and transfer it to the elevator, a sand conditioning belt pivoted adjacent the front of the frame in advance of the elevator and adapted to receive sand from the elevator and discharge it in front of the frame, and operating means associated with said sand conditioning belt for moving the same about its pivot whereby the direction of discharge of the sand may be changed.

2. In a device of the character described, a movable supporting frame, a screening mechanism supported longitudinally of the frame and adapted to receive molds, shakeout and separate castings from sand, a pair of spaced longitudinally extending inclined rails supported on said frame above the screening mechanism, each rail being of channel formation with its forward lower end being inclined downwardly relative to the rest of the rail and having its upper wall removed to provide an enlarged entrance portion, a mold conveyor normally located in inclined position in advance of the screening mechanism and having rail engaging rollers for permitting the conveyor to be moved to inoperative position on said rails, a pair of supporting wheels mounted on the front of said mold conveyor, said wheels being adapted to ride upon and be supported by said enlarged entrance portions when the conveyor is raised to inoperative position, and means carried by said frame for raising said conveyor on said rails to an inoperative position.

STANLEY B. DAVIES.
